ATTORNEY

UNITED STATES PATENT OFFICE.

ERNEST J. STEGMAYER, OF DETROIT, MICHIGAN.

WINDOW-STRAP CLUTCH.

1,307,936.

Specification of Letters Patent. Patented June 24, 1919.

Application filed July 25, 1917, Serial No. 182,701. Renewed May 10, 1919. Serial No. 296,467.

To all whom it may concern:

Be it known that I, ERNEST J. STEGMAYER, a citizen of the United States, residing at Detroit, in the county of Wayne and State 5 of Michigan, have invented certain new and useful Improvements in Window-Strap Clutches, of which the following is a specification.

This invention relates to a window strap 10 clutch and the principal object of the invention is to provide a device of this nature which will hold the windows in automobile doors at any desired position.

Another object of the invention is to provide simple and efficient means whereby the clutch may be actuated to release the strap.

Another object is to provide means whereby the weight of the window tends to make the clutch grip the strap tighter.

Another object of the invention is to 20 cover the securing means of the clutch with the material by which the automobile is trimmed, so as to give the automobile a neater appearance.

The invention also consists in certain 25 other features of construction and in the combination and arrangement of the several parts, to be hereinafter fully described and specifically pointed out in the appended 30 claims.

In describing my invention in detail, reference will be had to the accompanying 35 drawings, wherein like characters denote like or corresponding parts throughout the several views, and in which:

Figure 1 is a front view of the invention, with part broken away.

Fig. 2 is a longitudinal sectional view.

Fig. 3 is a section on line 3—3 of Fig. 1.

In this drawing 1 indicates a part of the 40 automobile door which is provided with the window 1' and 2 represents a strap one end of which is secured to the window. The door is provided with an outer shell of metal 45 1' which forms an opening 1^a to receive the window. The strap passes over the top of the door, down through a casing 3 and through a transverse slot 2^a in the door and which communicates with the opening 1^a. The casing 3 is made of metal or any other 50 suitable material and is secured to the wood-work of the door and at the lower part of said casing I locate my clutch which consists of the casing preferably made of one piece 55 of metal bent to form the top and sides of the casing and having the outwardly extending flanges 5 provided with screw-holes for receiving the screws 6 by which the casing is secured to the door. These ends of the casing above said flanges 5 are bent to 60 form recesses 7 to receive the trimming material 8 so that the screws 6 are covered by this material. The material forming the ends of the casing is cut and bent to form ears 9 and said ears are provided with holes 10 for receiving the journals of the clutch member 10. Said member consists of a plate provided with the journals 11 at its ends by which the plate is mounted and has rocking movement in the casing and the front edge 70 of said plate is bent downwardly as at 12 to grip the strap. At its rear edge an ear 13 is left on the plate and said ear is bent backwardly upon the plate to form a seat for the inner end of the push button 14, said 75 button being held on the seat by means of a light spring 15, so as to prevent rattling of the button. V-shaped springs 16 are located between the top of the casing and the plate for forcing said plate, with its bent 80 edge 12, in engagement with the strap. By the pressure of the springs 16, the clutch member is normally inclined downwardly so that as the strap moves upwardly through the casing 3, the grip of the clutch member 85 is intensified thereon. 17 represents a part on the door covering the end of slot 2^a. It will be seen that the window 1' hangs on the strap 2 and the weight of the window has a tendency to draw the free end of the 90 strap out of the top of the clutch. But as the clutch plate is already engaged with the strap the strain caused by the weight of the window, will intensify the engagement of the clutch plate with the strap 2 so that the 95 window will remain in a permanent position. To lower the window, push the button 14 which releases the engagement between plate 10 and the strap 2. When the window has been lowered as far as desired, release 100 the button and the plate 10 will resume engagement with strap 2 and hold the window in that particular position. Now as the window is lowered into the recess in the door, the strap 2 is naturally pulled along 105 down with it which is permitted as explained by releasing plate 10 by pushing button 14. When the window has been entirely lowered, there is still a few inches of the strap 2 projecting into the slot 1^a in 110

the door. To raise the window pull up on the strap and when window has been raised to the desired height push the strap 2 down into clutch and the window will remain in 5 that position. As the window is raised the free end of the strap 2 passes through the clutch, then down through slot 2^a and down into window recess 1^a.

It is thought from the foregoing that the 10 advantages and novel features of my invention will be readily apparent.

I desire it to be understood that I may make slight changes in the construction and in the combination and arrangement of the 15 several parts, provided that such changes fall within the scope of the appended claims.

I claim as my invention:

1. In combination with a door having a vertical slot therein to receive a slidable window and a downwardly inclined slot below 20 the top of the door to communicate with said vertical slot, of a strap connected to said window and passing over the top of said door, then down the side of the door 25 and through the inclined slot, and means arranged between the inclined slot and the top of the door for engagement with the strap to retain said window in adjusted position.

30 2. In combination with a door having a vertical slot therein to receive a slidable window and a transverse slot to communicate with said vertical slot, of a strap connected to said window and passing over the top of 35 said door and to the transverse slot, a casing secured to the door between the transverse slot and the top of the door, a normally downwardly inclined clutch member pivoted therein and having its lower end 40 engaging the strap to retain the window in adjusted positions, spring means for retaining said clutch member in its normal inclined position, and means for swinging the

clutch member out of engagement with said strap.

3. In combination with a door having a vertical slot therein to receive a slidable window and a transverse slot to communicate with said vertical slot, of a strap connected to said window and passing over the top of 50 said door and through the transverse slot, a casing secured to the door between the transverse slot and the top of the door, a normally downwardly inclined clutch member pivoted therein and having its lower end engaging the strap to retain the window in adjusted 55 positions, V shaped springs each having one arm engaging the inclined clutch member and the other arm engaging said casing to retain the clutch member in its normal position, and means for swinging the clutch member out of engagement with the strap.

4. In combination with a door having a vertical slot therein to receive a window and 60 a transverse slot to communicate with said vertical slot, of a strap connected to said window and passing over the top of said door and through the transverse slot, a casing secured to said door between the transverse slot and the top of the door, a normally downwardly inclined clutch member pivoted 65 therein and having its lower end engaging the strap to retain the window in adjusted positions, spring means for retaining said 70 clutch member in its normal inclined position, a push button slidably mounted in said casing, and a spring normally retaining said push button in engagement with the clutch member.

In testimony whereof I affix my signature in presence of two witnesses.

ERNEST J. STEGMAYER.
